UNITED STATES PATENT OFFICE.

JOHN H. BELL, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,337,748.

Specification of Letters Patent. Patented Apr. 20, 1920.

Application filed November 21, 1917. Serial No. 203,083.

To all whom it may concern:

Be it known that I, JOHN H. BELL, a citizen of the United States, residing at South Orange, in the county of Essex and 5 State of New Jersey, have invented certain new and useful Improvements in Telegraph Systems, of which the following is a full, clear, concise, and exact description.

This invention relates to telegraph systems and more particularly to submarine telegraphy.

The principal object of this invention is to provide an improved organization of apparatus for overcoming the phenomenon 15 known as "wandering zero" experienced in line conductors having high electrostatic capacity.

The invention is more particularly applicable to systems in which an uninterrupted alternating current, preferably of 20 sine-wave form, is impressed on the cable, the message impulses being in the form of augmented half waves of either positive or negative polarity, *i. e.*, half waves of increased amplitude.

In such systems when two or more augmented half waves of positive polarity, for example, are separated by negative half waves of normal amplitude, there results a 30 cumulative charge on the cable which manifests itself as an apparent shifting of the zero line, so that in the case in question the current at the receiving end of the cable instead of alternating from positive to negative might appear simply as a fluctuating positive current.

With some forms of receiving devices, such, for example, as the siphon recorder, it is possible to read such distorted signals 40 without much difficulty.

When, however, an automatic recording of the signals is desired, as in printing telegraphy, it becomes necessary to employ marginal receiving devices to differentiate 45 between augmented half waves and normal half waves. In such cases it follows that if the distortion of signals above mentioned is not corrected or compensated for in some way, the operation of such marginal device 50 may be seriously interfered with.

The present invention provides a receiving system which automatically compensates for such distortion. The arrangement employs two receiver relays or impulse receiving means with a local circuit under the

control of each to accelerate the action of the other.

The arrangement chosen as a preferred embodiment of this invention is illustrated diagrammatically in the accompanying 60 drawing, in which only so much of a telegraphic receiving equipment is shown as will be necessary to a clear understanding of the system.

The drawing, Figure 1, is a schematic circuit arrangement of a telegraph receiver equipment. Figs. 2 and 3 each similarly illustrate respective alternate arrangements of the receiving equipment shown in Fig. 1.

In describing the operation of this system 70 attention will first be directed to the drawing, Fig. 1. A telegraph line indicated by the reference numeral 1 is connected serially through the line windings 3 and 23 of polarized relays 2 and 22, respectively, and an 75 artificial line AL to earth. For the relay 2 a second circuit may be traced from a source of current 8, an impedance coil 9, a local winding 4 of this relay, a resistance unit 10, thence through a condenser 11 to 80 earth. In a similar manner a circuit extends from the battery 8 through an impedance coil 29, a local winding 24 of the relay 22, a resistance unit 30, thence through a condenser 31 to earth. The 85 armatures 5 and 25 of the relays 2 and 22 respectively, are normally biased to the position in which they are shown, thereby establishing a first circuit which may be traced from a source of current 40, through 85 the left-hand winding of a relay 41, and the contacts 6 of the relay 2 to earth, and another similar circuit from the source 40, the right-hand winding of the relay 41 and the contacts 26 of the relay 22 to earth. 95 Currents through the circuits just traced act differentially in the relay 41 which, therefore, remains inert.

For convenience of description it will be considered that under an impulse of positive current from the line 1 the armature 5 of the relay 2 will move to close its contacts 7 while the same impulse will not affect the relay 22 except to increase the tension of its armature 25 in retaining its contact 26 closed. An impulse of negative current from the line 1 will accordingly set up an inverse action, whereby the armature of the relay 22 would move to close its contacts 27, while the armature of the relay 2 would 110

2

hold more firmly to its contacts 6. The relay 41 controls (by means not shown) any suitable signal receiving device, as a tape recorder or printing telegraph receiver, and 5 is energized at any moment that either the contacts 6 of the relay 2 or the contacts 26 of the relay 22 are open. Biasing of the relay armatures 5 and 25 may be effected by means of suitable retractile springs, or the 10 energy of the sensitizing or polarizing magnetism may be employed for this purpose by adjustments whereby a greater gap space would be present in the magnetic circuit at one side of the armature, or other convenient 15 design of the relay as will be readily understood by those skilled in the art. In order that the drawing would not be unnecessarily complex polarizing means for the relays 2 and 22 have not been shown.

20 Referring now to the local circuits of the relays, the condenser 11 is charged over the circuit already traced when the contacts 27 of the relay 22 are separated, and discharged to the earth connection extending from the 25 relay armature when the contacts 27 are closed. In a like manner separation of the contacts 7 of the relay 2 permits the condenser 31 to charge and the closing of these contacts discharges this condenser. The 30 direction relation between the line and local winding of each polarized relay is such that the charging and discharging of the respective condenser will always be accumulative with half-wave currents from the line circuit 1. It will, therefore, be obvious that an 35 impulse of positive current from the line 1, on moving the armature of the relay 2 to close its contacts 7, will thereby permit the condenser 31 to discharge through the winding 24 of the relay 22 in a direction to assist 40 the positive impulse through the line winding 23 in retaining the armature of this relay on its contacts 26. In phase with and immediately following the impulse of negative 45 current from the line 1, retraction of the armature of the relay 2 will be accelerated thereby, while the armature of the relay 22 will move to close its contacts 27. In connection with these operations, at the instant 50 the contacts 7 of the relay 2 separate, charging of the condenser 31 takes place through the winding 24 of the relay 22 to assist the negative current in the winding 23 in moving the armature 25 to close its contacts 27.

55 On the instant the contacts 27 close, the condenser 11 discharges through the winding 4 of the relay 2, thereby assisting the remaining portion of the negative impulses in the winding 3 in bringing the armature of this 60 relay to firmly close its contact 6.

The relays 2 and 22 should be of suitable design or adjusted in such a manner that although they will remain inert, in the position shown, under currents of a predetermined strength they will nevertheless re-

spond to currents of an incremented or maximum strength. Such range limits of adjustments should be made on the basis of the accumulative action of both the line current and the static or condenser current in each 70 relay as already described. It will therefore, be clear, that although these polar relays will remain inert under alternating currents of a minimum strength, they will respectively respond to alternations or half-wave currents of a maximum strength. 75

In the further description of this system let it be assumed that the armature of each polar relay is biased by means of a suitable adjustment of the magnetism employed for 80 establishing their polarization. It will be mentioned that in the drawing biasing springs have been shown merely as a matter of convenience in order that the system may be more readily understood. If, now, 85 two half waves of positive polarity and of maximum strength from the line 1 are separated by a negative half wave of minimum strength the relay 2 will respond to the two positive alternations and each time its 90 contacts 6 disconnect the left-hand winding of the relay 41 in response thereto, the current from the source 40 already present in the right-hand winding of the latter relay, as already described, will effect the operation 95 of this relay. Now, assuming that the third alternation of positive sign and maximum strength is followed by a negative alternation of maximum strength the latter impulse would not rise to its pre- 100 scribed volume, due to the preponderance of the positive charge retained by the cable. Since the armatures of the polarized relays when operating will move relatively in phase with the wave currents, 105 at the instant the assumed negative alternation begins, the armature of the positive responding relay 2 will start on its return trip, thereby separating the contacts 7. Thereupon the condenser 31 receives a 110 charge from the battery 8 and this current through the windings 24 acts cumulatively with the negative impulse in the line winding 23 of the relay 22 to move the armature 25 to close its contacts 27. 115

Although the distortion may have reduced the negative impulse to a strength below a value alone sufficient to operate the relay 22, the augmenting action of the condenser discharge creates the additional energy required to move the relay armature. Separation of the contacts 26 of the relay 22 disconnects the right-hand winding of the relay 41 and at the instant the contacts 27 of the polar relay close, the circuit is completed to discharge the condenser 11, the current of which acts through the winding 4 to assist the negative alternation present in the line winding 3 in quickly and firmly closing the contacts 6 of this relay, follow- 125 130

ing which current from the battery 40 traverses the left hand winding of the receiving relay 41, which thereupon responds. The converse of this action would, of course, take 5 place with respect to the relays 2 and 22 for a positive impulse under conditions similar to those assumed.

The purpose of the impedance effect of the units 9 and 29 and also the effect of the 10 resistance units 10 and 30 is to lag or retard the currents set up by the condensers 11 and 31, respectively, in order that the currents through the relay windings 4 and 24 will be brought more nearly in phase with 15 current pulsations through the line windings 3 and 23.

From the foregoing description it will be clear that contacts controlled by the relay 2 control the action of currents through 20 operating windings on the relay 22 and in a like but converse manner the same control is effective from the relay 22 to the relay 2.

Referring to the drawing (Fig. 2) similar characters of reference have been employed in this drawing to indicate parts that are like or that correspond to parts in the figure already described. This alternate arrangement differs from the first principally through the fact that the connections to the 25 contact stops of the relays 2 and 22 are reversed. By this change, on the instant the normal contacts (6, 26) of either relay open, the condenser associated with the local winding of the opposite relay is charged, thereby 30 affecting that relay in a manner as already described. At the instant the normal contacts of either polar relay close, the condenser of the opposite relay is discharged through its associated winding. It may also 35 be pointed out that the translating relay 41 is normally on open circuit, the contact 7 of the relay 2 completes an energizing circuit through its left-hand winding in response to an incremented half wave of 40 positive current from the line 1, while a negative impulse of similar strength from the line will operate the relay 22, whereby its contacts 27 establish energizing current through the right-hand winding of the 45 relay 41.

In considering the alternate arrangement shown in Fig. 3, an incremented half wave of positive current from the line 1 will move the armature of the relay 2 to close its contact 7, thereby establishing the source of current 50 40 through the winding of a receiver control relay 42 and a resistance unit 43 to earth. In addition to operating the relay 42, current also traverses a resistance unit 44 to a connection intermediate the two spool sections forming the local circuit windings 24 of the relay 22. This current in branching acts through the right-hand coil to charge the condenser 31 and completes circuit through the left-hand coil and

the resistance unit 30 to earth. The steady current through the left-hand coil of the relay 22 is of such strength that it will exert only sufficient pressure on the armature 25 to approximately relieve the biasing force 70 by which it is held in the position shown. If now the first alternation of incremented positive current from the line 1 is followed by an incremented inverse alternation the latter current will act to move the armature of each relay to the left. On the instant the contacts 7 of the relay 2 separate, the condenser 31 discharges through the winding 24 of the relay 22 and the resistance 75 30 to earth, thereby augmenting the negative alternation from the line 1 in moving the armature 25 to close its contacts 27. Through the latter contacts the battery 40 is connected through the winding of a second receiver control relay 45 and a resistance unit 46 to earth. It will be noted 80 that the contacts of the latter relay are connected in parallel with the contacts of the relay 42. Therefore, these relays serve to control the same receiving circuits (not 85 shown). Closure of the contacts 27 of the relay 22 also includes current from the battery 40 through a resistance unit 47 to charge the condenser 11 and also to maintain a steady current through the left-hand 90 coil of the winding 4 of the relay 2 and a resistance unit 10 to earth. In case a third alternation from the line 1 is of incremented value, its polarity being positive, at the instant the contacts 27 separate as the armature 95 of the relay 22 starts on its return or restoring trip, the condenser 11 will discharge through the winding 4 and resistance unit 10 to earth, thereby augmenting the action of the line impulse in moving the 100 armature of the relay 2 to close its contacts 7. The assisting action is reciprocal with respect to the two line relays 2 and 22 and it may be mentioned that at the instant the condenser 11 or 31 receives a charge, the 105 110 charging current acts differentially through the right-hand coil section of the winding 4 or 24, respectively, with respect to the steady current through the left-hand portion of this winding.

From the foregoing description it will be clear that in addition to controlling the translation of impulses from a line circuit to local receiving apparatus, each of the line relays controls circuits on the other 115 120 relay, respectively, to render it more sensitive to impulses from the line to which it should respond.

What is claimed is:

1. In a telegraph receiver, a first and a second impulse receiving means, and means controlled by each one of said impulse receiving means for accelerating the response to impulses respectively by the other receiving means.

2. In a telegraph receiver, a first and a second relay respectively responsive in the reception of positive and negative impulses, and a condenser worked by each relay to respectively aid the operation of the other relay.
3. In a telegraph receiver, a first and a second relay for respectively responding to impulses of opposite polarities, message translating means controlled by said relays, a condenser for each relay respectively under the control of the other relay for respectively accelerating the action of said relays.
4. In a telegraph receiver, a plurality of impulse receiving devices, each one selectively responsive to current of respectively predetermined characteristics, and means associated with each of said devices and respectively controlled by another one of said devices to render it effective to accelerate the response of the respectively associated device.
5. In a telegraph receiver, a first and a second relay respectively responsive to currents of opposite polarities, signal translating means controlled by said relays, a condenser controlled by each relay for accelerating respectively the response of the other relay, and means for controlling the electrical time constants of said condenser circuits.
6. In a telegraph receiver, a first and a second line relay respectively responsive to currents of opposite polarities, a first and a second winding for each of said relays, 35 a condenser included with the second winding of each of said relays, contacts for each relay to control the circuits of a signal translator, said first winding of each relay arranged for the reception of impulses from 40 a line circuit, the second winding of each relay respectively controlled by said contacts of the other relay to establish current therein which will aid an impulse of current through the first winding of the same relay. 45
7. In a telegraph receiver, a first and a second compound wound relay respectively responsive to current of predetermined characteristics, one winding on each relay arranged for the reception of impulses from 50 a line circuit, contacts for each relay to control a signal translator circuit, a condenser and an impedance coil included with the other winding of each relay, a source of current, said contacts of each relay arranged 55 to charge and discharge the condenser of the other relay respectively in order that the action of a signaling impulse through the first winding will be augmented by the electrostatic current through the other winding. 60

In witness whereof, I hereunto subscribe my name this 16th day of November, A. D. 1917.

JOHN H. BELL.
